METHOD OF TRANSMITTING SECRET MESSAGES

Paul Kotowski and Kurt Dannehl, Berlin, Germany, assignors to Telefunken Gesellschaft für Drahtlose Telegraphie m. b. H., Berlin, Germany, a corporation of Germany

Application May 6, 1936, Serial No. 78,184
In Germany May 9, 1935

1 Claim. (Cl. 179—1.5)

The present invention relates to a method of secret telephony in which a disturbing oscillation is superposed on the speech oscillation, said disturbing oscillation comprising the whole frequency band of the human voice and having an amplitude only slightly larger than the maximum voice amplitude. By superposing, every combination of the two oscillations (addition, modulation or both) shall be understood. Such a disturbing band equally distributed over the whole voice frequency range is, for instance, known as film, or disk noise at the mechanical or electromagnetic sound reproduction of sound pictures or disks.

15 The invention will best be understood by referring to the accompanying drawing, in which: Fig. 1 is a curve showing the proportional relationship between the speech and disturbing oscillations known in the prior art;

20 Fig. 2 is a curve showing the proportional relationship between the speech and disturbing oscillations of this invention;

25 Fig. 3 is a schematic detail of a rotating generator which produces the disturbance noise of this invention.

Methods of secret telephony are known in the prior art in which through the superposition of any disturbing energies on the speech energy cover up the speech and cause what may be 30 called a "ciphering." Methods of this type have not become popular especially in the field of wireless telephony, however, since according to the requirements demanded of the "ciphering," the disturbance voltage must be three to five times 35 the maximum speech voltage so that the useful modulation of the transmitters becomes thereby so low that the transmitter power must be considerably increased in order to obtain the same range as in the case of undisturbed speech (an 40 increase ten to twenty five times). This is clearly shown by Fig. 1, in which curve ST indicates the disturbance voltage and SP the speech voltage.

The invention is based upon the teaching that 45 a disturbance analogous to the noise voltages of talking films, record plates or tubes, is sufficient to obscure the speech to a point of complete unintelligibility already at amplitudes which are 1.2 to 1.3 times larger than the maximum speech amplitudes. Such a film, or disk noise has thus 50 an ideal disturbing band for which a relatively small amplitude is sufficient in order to render the speech oscillations undecipherable to a suitable degree. Where the ideal disturbance spectrum is not fully attained, a larger disturbing 55 amplitude is required. A generator for such noise

voltage is suitably such as to provide a frequency spectrum of approximately the same strength throughout the limits between the zero frequency and the highest frequency used, and is shown by curve *a* in Fig. 2. Also, in this figure, ST represents the disturbance voltage and SP the speech voltage. Smaller generators of disturbance and disturbance lines will be adequate if a narrower frequency band underlies the calculation of the disturbance generator, for instance in accordance with the curve *b* of Fig. 2. In this case, the disturbance is distributed over the frequency band in approximately the same manner as the speech energy. It has then suitably a slightly pronounced maximum between 500 and 1000 cycles. The disturbance producer may be designed as 5 rotating generator for instance in that a rotatable disk S shown in Fig. 3 of irregular shape and having slots or pointed projections, produces short pulses in a corresponding scanning organ AT through electrical, mechanical or optic means, whereby the duration of an individual pulse is approximately equal or shorter than the half 10 cycle of the highest disturbance frequency used. When narrowing the band of the disturbance 15 energy, then the irregularly distributed individual pulses are so dimensioned that the majority thereof have a duration from 0.2 to 0.8 milli-seconds. Such a disturbance generator 20 could for instance also be obtained in that a disturbing noise known to be sufficient (record, plate, talking film, water fall, etc.) is transformed 25 into fluctuations of light, and these fluctuations are photographed on a rotating plate. In like manner, an endless film band or record plate 30 with endless grooves could be utilized. As compared with a round disk with irregularly pointed 35 projections provided mechanically thereon, this method has the advantage that the disturbance 40 patterns produced therewith can be easily produced at the receiver through a copying method in any desired number for the purpose of deciphering. The parts of mechanical disturbance 45 generators by which the frequency is determined can be produced in simultaneous ways for instance by means of machining a plurality of discs 50 mounted on a single mandrel.

In order to emphasize the rotation frequency 55 of the disturbance generator in the mixture of the disturbing frequencies and which is of practical usefulness for many purposes, a mark K (in Fig. 3) is provided at a certain place on disc S. (Pause in the disturbing noise, or definite tone, or eventually for synchronizing purposes an especially large disturbance impulse.)

Under certain conditions, instead of extending the uniform disturbance spectrum from zero to the highest frequency as shown by curve ST of Fig. 2, it may be desirable to filter out by electrical filters totally or partially the range of for instance 200-2500 cycles at speech transmission.

The particular advantage of the method described by this invention resides in that the transmitter can be more effectively modulated for the benefit of the speech, in other words at equal speech strength, a smaller powered transmitter can be used.

The ciphering can be provided either by superposing by way of low-frequency the disturbing noise directly on the speech, or else by modulating an auxiliary high-frequency with the disturbing noise and thereafter superposing this auxiliary frequency on the actual carrier frequency.

At the receiver side the deciphering is carried out accordingly. By means of an identical disturbance generator operating in synchronism and in equal phase with that at the transmitter side, the alternating disturbance current having the

proper phase position and amplitude is superposed on the arriving speech having been "ciphered" by the disturbance noise, so that thereby the disturbance noise disappears.

What is claimed is:

The method of transmitting signal messages which consists of superimposing on the messages to be transmitted a disturbance noise formed by irregular alternating current, said alternating current forming the disturbance noise having a frequency spectrum which covers substantially the entire speech frequency spectrum, the amplitude of the frequency spectrum exceeding but slightly the amplitude of the message frequencies, transmitting the combined message and disturbance noise on a high frequency carrier, receiving said combined message and disturbance noise in a proper phase position with respect to the phase of the combined transmitted message to make said disturbance noise disappear, and removing said disturbance noise before translation of said message.
